(57) **CLAIM**

The ornamental design for a carrier for sports boards, as shown and described.

DESCRIPTION

FIG. 1 is a front view showing the sports board carrier of my design;

FIG. 2 is a side view of the carrier of my design as viewed from the right side of FIG. 1, the left side view being the mirror image thereof;

FIG. 3 is a front perspective view of the carrier of my design; and,

FIG. 4 is a rear perspective view thereof.
